FEEDING MECHANISM

George P. McGraw, Jr., Downers Grove, Ill., assignor to Western Electric Company, Incorporated, New York, N.Y., a corporation of New York

Filed Jan. 30, 1957, Ser. No. 637,163

9 Claims. (Cl. 242—67.2)

This invention relates to apparatus for advancing material to a utilization station, and more particularly to apparatus for advancing an extremity of a web into close proximity with a winding device to preclude sagging of the web where the web is of such thickness that even a small unsupported portion will sag due to its own weight. It is an object of the invention to provide improved apparatus of this character.

In the present invention, the disclosed apparatus has been designed to feed webs of metal foil and dielectric to capacitor winding machines, but it will be readily understood from the following description that the invention is equally applicable to other types of web winding machines.

Electrostatic capacitors are generally formed by winding alternate layers of metal foil and dielectric upon winding arbors or capacitor cores. In the past, such operations as inserting the core, attaching the webs to the core, severing the webs when the winding operation is completed, and sealing the ends of the webs to the capacitor to prevent unwinding have all been hand operations. To permit high speed production of electrostatic capacitors, it became necessary to design a capacitor winding machine which would automatically perform the aforementioned operations. Such a machine is disclosed in the co-pending application of J. R. Marcus et al., filed January 30, 1957, Serial No. 637,154. The present invention has been designed for use in conjunction with the above-mentioned machine to feed the ends of the webs of dielectric and foil to the rotating capacitor core at timed intervals.

When winding electrostatic capacitors, and particularly the smaller sizes, problems are encountered due to the extreme thinness of the webs of material used. The webs of material are so thin that even a small portion of the end of the web projecting beyond its support will tend to sag due to the force of gravity. Of course, if the web is fed vertically, this problem does not arise. However, when winding multilayer objects such as capacitors, it is not possible to feed all of the webs along a vertical line. Consequently, an automatic device for feeding the ends of webs to a rotating capacitor core to be picked up by the core and wound thereon must be so designed that the end of the web is supported to a point just short of the rotating core to preclude sagging until it is picked up by the core.

It is another object of this invention to provide an apparatus which will feed thin webs into close proximity with a rotating core to permit the core to pick up the end of said web.

It is another object of this invention to provide a web feeding apparatus which will support a thin web, without sagging, adjacent a rotating core upon which the web is to be wound.

It is still another object of this invention to provide a pair of movable flat thin guides to position a web in close proximity with a rotating core and a pair of feed

2

rollers for feeding the web between the guides and into contact with the core to be wound thereon.

With these and other objects in view, the present invention contemplates a pair of flat thin web guides slidably mounted for movement toward and away from a rotatably mounted capacitor core, and a pair of feed rollers for advancing a web between the guides when the guides are adjacent the core. Drive means are provided for rotating the core, for advancing and retracting the guides, and for imparting rotation to the feed rollers to advance the web between the guides and into contact with the core to be gripped and wound thereon.

Other objects, advantages, and novel features of the invention will become apparent upon consideration of the following detailed description in conjunction with the accompanying drawings wherein:

Fig. 1 is an elevation, partially in section, of a winding apparatus provided with two feeders embodying the principal features of the invention, one in a retracted position with a web being drawn therethrough and the other in an advanced position feeding the end of a second web between the rotating core and the first web;

Fig. 2 is a view taken along the line 2—2 of Fig. 1 illustrating the manner in which the feed rollers fit into slots formed in the guides; and

Fig. 3 is a view taken along the line 3—3 of Fig. 1 illustrating the manner in which the slidable guides are mounted.

Attention now is directed to the drawings, wherein like numerals of reference designate like parts throughout the several views; and to Fig. 1 in particular wherein is disclosed a side frame 11 having feeder supporting brackets 12 mounted thereon. Feeder slides 14 are slidably secured to the supporting brackets 12 by means of trapezoidal projections 15 (Fig. 3). The feeder slides 14 are provided with thin flat duck-bill extensions 16 and 17 which are separated by a narrow gap to provide a passage for the webs 19 and 20.

The feeder slides 14 have feed rollers 21 pivotally mounted thereon. Clamping members 22 are pivotally mounted on the feeder slides 14 by means of pins 24 and carry second feed rollers 25 rotatably mounted on the free extremities thereof. Cam followers 26 are rotatably secured to the pivoted clamping members 22 and are positioned so as to engage cam members 27, secured to the supporting brackets 12, when the feeder slides 14 are in their fully retracted positions to separate the feed rollers 21 and 25. Leaf springs 28 are fastened to the feeder slides 14 and normally urge the rollers 25 into contact with the rollers 21 within slots 29 (Figs. 1 and 2) whenever the cam followers 26 are not engaged by the cam members 27.

The winding shaft 30 is provided to rotate a capacitor core 31 and may be driven by any suitable means through belt 32 and sheave 34. The winding shaft 30 has a gear 35 fixed thereto which imparts rotation to a feed shaft 36 through a second gear 37. A feed drive roller 39 made of rubber or other similar material is in rolling contact with the feed shaft 36 and is driven thereby.

Coaxial with the winding shaft 30, but separately driven by a variable speed drive (not shown), are a pair of feed cams 40. A lobe 41 is formed on one of these cams and a lobe 42 on the other. The variable speed drive permits changes to be made in the ratio of winding shaft speed to feed cam speed to adjust the capacitance of the finished product. A pair of feed cam followers 44, carried by cranks 45, are in rolling contact with the cams 40; one follower contacting each cam. The cranks 45 are secured to shafts 46 which are journaled in projections 47 formed on the supporting brackets 12. The opposite extremities of the shafts 46 have rocker arms 48 secured thereto. The rocker arms 48 are con-

nected to the feeder slides 14 by means of cross heads 50 (Fig. 1) to convert rotary motion of the rocker arms 48 into reciprocatory motion of the feeder slides 14. Springs 49 are provided to urge the slides 14 outwardly and thus maintain the followers 44 in contact with the cams 40.

Operation

In order that a better understanding of the invention may be had, its mode of operation will now be described. A capacitor core 31 is first mounted for rotation between the end of the winding shaft 30 and a reciprocably mounted live center (not shown). The webs 19 and 20 are then inserted into the slots 51 and are fed inwardly by hand until the ends of the webs project just beyond the extremities of the duck-bills 16 and 17. Passage of the webs 19 and 20 between the feed rollers 21 and 25 is possible because the feed rollers have been separated due to the action of the cam followers 26 and cam members 27; both of the feeder slides 14 being in their retracted positions at this time. The winding shaft 30 is then started in motion.

As the winding shaft 30 begins to rotate, the lobe 41 on one of the feed cams 40 engages the feed cam follower 44 on the lower feeder assembly (Fig. 1). This causes the associated feeder slide 14 to begin moving inwardly. When the cam follower 26 rides down the inclined surface of the cam member 27, the feed rollers 21 and 25 grip the web 19 and pull the web from the supply roll as the feeder slide 14 moves into the feeding position.

When the feeder slide 14 reaches its inner position, a rubber roller 52, fixed to the shaft mounting the feed roller 21, frictionally engages the roller 39 and starts to rotate the feed rollers 21 and 25 to cause the web 19 to advance toward the capacitor core 31 from between the duck-bills 16 and 17. The capacitor core 31 is provided with a plurality of slots opening on the interior thereof. A vacuum pump (not shown) creates a partial vacuum within the capacitor core 31 in a manner more fully described in the aforementioned co-pending application. The inrush of air into the slots in the capacitor core 31 pushes the extremity of the web 19 against the capacitor core 31 and the partial vacuum holds the web 19 in this position. After the winding shaft 30 has made a few more turns, the web 19 is securely held thereto. An overrunning clutch 54 (Figs. 2 and 3) interconnects the roller 52 and feed roller 21 to permit the feed rollers 21 and 25 to free-wheel whenever the web 19 is being pulled by the shaft 30 at a greater linear speed than the peripheral speed of the feed rollers 21 and 25.

Continued rotation of the feed cams 40 permits the feed cam follower 44 to ride down the side of the lobe 41 and thus retract the associated feeder slide 14. The feed rollers 21 and 25 free-wheel, as mentioned above, while the feeder slide is moving toward its retracted position. As the feeder slide reaches its retracted position, cam follower 26 engages cam member 27 to rotate the clamping member (clockwise in Fig. 1) and thus separate the feed rollers 21 and 25.

Additional rotation of the cams 40 causes the lobe 42 to engage the feed cam follower 44 on the upper feeder assembly. The upper feeder assembly then grips the web 20 and moves into the position shown in Fig. 1 in exactly the same manner as that described for the lower feeder assembly. As the extremity of the web 20 emerges from between the duck-bills 16 and 17, it is inserted between the web 19 and the material already wound on the capacitor core 31. This permits the web 20 to be picked up by the rotating core and to be wound thereon in a position underlying the material from the web 19. As the cam follower 44 rides down the side of the lobe 42, the upper feeder slide 14 retracts in exactly the same manner as that described for the lower feeder assembly.

When winding capacitors in this manner, four or more webs of dielectric and metal foil are normally required. However, only two rolls of capacitor material are illus-

trated in the drawings for purposes of simplification, inasmuch as only two webs need be shown to illustrate the principle of operation of the present invention. It is manifest that additional feeder assemblies could be added to the disclosed apparatus in order to utilize additional rolls of material.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. An apparatus for feeding the extremity of a thin web to a winding device comprising a pair of rotatably mounted feed rollers, means for urging said rollers into abutting relationship to grip a web therebetween, means for advancing said rollers toward a winding device, drive means for imparting rotation to said rollers to advance the web being gripped to the winding device, an overrunning clutch included in said drive means to permit the winding device to withdraw the web without tearing at a linear speed greater than the peripheral speed of the feed rollers, means for retracting said advancing means, and means for separating said rollers when the advancing means is fully retracted to release the web.
2. An apparatus for feeding the extremity of a thin web to a winding device comprising a pair of rotatably mounted feed rollers, means urging said rollers into abutting relationship to grip a web therebetween, means for moving said rollers toward a winding device, drive means for rotating said rollers to feed the web to the winding device when the moving means reaches its advanced position, an overrunning clutch included in said drive means to permit withdrawal of the web from between the rollers by the winding device at a linear speed greater than the peripheral speed of said rollers, means for retracting the advancing means, and means for opening said rollers when the advancing means is fully retracted to release the web.
3. Apparatus for feeding material to a utilization station, said apparatus comprising means for supporting a free end portion of said material, means for advancing said supporting means toward the utilization station to bring the free end of said material to said utilization station and for retracting said supporting means to prevent interference thereof with said utilization station, one-way material feeding means carried by said supporting means, said one-way feeding means resisting movement of said material with respect to said supporting means in a direction away from said utilization station and permitting movement of said material with respect to said supporting means in a direction toward said utilization station, and means for actuating said one-way feeding means to feed said material toward said utilization station while said supporting means is in advanced position.
4. Apparatus for feeding material to a utilization station as specified in claim 3 wherein said actuating means are in turn actuated by advancement of said supporting means to the advanced position thereof.

5. Apparatus for feeding flexible material to a material winding device, said apparatus comprising means for supporting a free end portion of said flexible material, means for advancing said supporting means toward said winding device to bring the free end of said material immediately adjacent said winding device and, for retracting said supporting means to permit the winding of a substantial body of said material on said winding device without interference by said supporting means, one-way material feeding means carried by said supporting means, said one-way feeding means resisting movement of said material with respect to said supporting means in a direction away from said winding device and permitting movement of said material with respect to said support-

ing means in a direction toward said winding device, and means for actuating said one-way feeding means to feed said material toward said winding device when said supporting means is in advanced position.

6. Apparatus for feeding flexible material as specified in claim 5 wherein said actuating means are in turn actuated by advancement of said supporting means to the advanced position thereof.

7. Apparatus for feeding flexible material as specified in claim 5 wherein said one-way material feeding means include a pair of cooperating feed rollers and an overrunning clutch through which said feed rollers are driven.

8. Apparatus for feeding flexible material as specified in claim 7 wherein said feed rollers are driven by friction rollers, one of said friction rollers being mounted on said supporting means and the other being mounted with said winding device for rotation therewith, said friction rollers being operatively engaged upon advancement of said supporting means toward said winding device.

9. Apparatus for feeding flexible material to a material winding device, said apparatus comprising means for supporting a free end portion of said flexible material, means for advancing said supporting means toward

said winding device to bring the free end of said material immediately adjacent said winding device and for retracting said supporting means to permit the winding of a substantial body of said material on said winding device without interference by said supporting means, one-way material feeding means carried by said supporting means, said one-way feeding means when actuated serving to advance said material toward said winding device with respect to said supporting means and at all times serving to permit advancement of said material toward said winding device with respect to said supporting means, and means for actuating said one-way feeding means to feed said material toward said winding device when said supporting means is in advanced position.
